AMMUNITION ABRADING APPARATUS

Harvey J. Hackman, Kings Mills, Ohio, assignor
to Remington Arms Company, Inc., a corpora-
tion of Delaware

Application March 11, 1941, Serial No. 382,689

3 Claims. (CL. 51—108)

This invention relates, in general, to ammunition, particularly to shot shells, and contemplates a novel method and means to abrade a portion of the surface of a shot shell. The invention is particularly adapted for use in connection with shot shells having waxed paper bodies but is adaptable to shell bodies of other materials.

It is to be understood that the invention as hereinafter disclosed may be a separate unit or may be but one station of a dial or straight line shot shell loading machine. Examples of typical loading machines wherein the present invention may constitute one station are illustrated in the patent to Chamberlin, No. 320,219, dated June 16, 1885, and the patent to Peters, No. 561,029, dated May 26, 1896.

An object of this invention is to provide an improved method of abrading a fiber tube. A further object is to abrade a fiber tube by utilizing the effect of maintaining relatively different peripheral speeds between rotating means and a fiber tube rotated by said means. An additional object is to support a paper tube between a plurality of surfaces moving relatively at different speeds, at least one of the surfaces having abrasive properties. A still further object is to feed a paper tube having a waxed surface between a plurality of abrading means rotating relatively at different peripheral speeds and to permit the tube to be supported and rotated by the abrading means, whereby the wax is removed from the surface of the tube. With these and other objects in view the invention consists in the novel constructions and combinations hereinafter more fully described.

In the drawings:

Fig. 1 shows an elevation of a portion of a dial machine including a single abrading unit.

Fig. 2 is a schematic view of a modification of the abrading machine of Fig. 1 and illustrates the assembly of a plurality of abrading units.

Fig. 3 is a plan view of the abrading unit on the right hand end of the assembly of units of Fig. 2.

Fig. 4 is a front view of two abrading units including the unit shown in Fig. 3.

Fig. 5 is a view of an abrading unit per se from the left hand end of the assembly.

Fig. 6 is a schematic view, in elevation, of a modified construction of the abrading unit.

Fig. 7 is a schematic plan view of the abrading unit of Fig. 6.

In the drawings, Fig. 1 represents a side elevation of one station of a dial machine includ-

ing a single abrading unit. It is to be clearly understood that the terms unit or abrading unit shall mean the assembly of a plurality of similar or dissimilar abrading means per se and driving means therefor. This unit comprises a frame or bed plate 1 which supports or to which is suitably secured an angle bracket 2 having a horizontally disposed extension or shelf portion 3. A pair of spaced openings or drilled holes 4, 5 are made in the shelf portion 3 in which bushings 6, 7 of a pair of abrading wheel spindles 8, 9 are suitably secured, the longitudinal axes of the bushings 6, 7 and spindles 8, 9 extending substantially at right angles to the horizontal surface of the shelf 3. The spindle 8 is rotatably retained in its bushing 6 by suitable fastening means indicated generally in the drawings by the retaining nut 10. The spindle 9 may be secured in its bushing 7 by means of a bearing collar 11 suitably mounted on the shelf 3. It will be appreciated, however, that any equivalent means of rotatably supporting the spindles is to be regarded as within the scope of this invention. The spindle 9 has a wedge-belt single groove pulley 12 keyed or otherwise secured to its upper end and connected by a suitable belt 13, preferably a V belt, to a single groove drive pulley 14. The latter is keyed to the motor shaft 15 of a motor 16. In the drawings the particular motor shown for driving the combination has power characteristics such as to turn up approximately 1725 R. P. M. It will be understood, however, that it is within the scope of this invention to use any suitable power source having similar characteristics or characteristics compatible with the abrasive used. A second single groove pulley 17, having a hub portion 18, is keyed or pinned near the lower end of the vertical spindle 9 under the bracket shelf 3, and is adapted to be spaced from the under surface of the shelf by a suitably arranged spacing collar 19. The pulley 17 is connected by a V belt 20 to drive a single groove pulley 21 having a hub portion 22 by which the pulley is keyed or otherwise fixed to the spindle 8. As shown in the drawings, the driven pulley 21 is preferably of the same dimensions as the driving pulley 17 whereby the driving ratio between the two pulleys is substantially one to one and the spindle speeds are substantially equal. If desired, however, this ratio may be varied by substituting pulleys of different diameters to procure relatively different spindle speeds. 23 represents an abrasive surface or disc, in this instance a wire brush wheel, having an integral hub portion 24 and suitable

fastening means 25 associated therewith whereby the wheel is pinned or keyed near the lower end of the spindle 9. In accordance with this invention a supporting plate or disc 26 is suitably fastened to the extreme lower end of the spindle 9 and immediately beneath the under surface of the abrading disc 23 so as to provide a substantially horizontal supporting surface for the abrading wheel. This feature is particularly desirable from the standpoint of providing means to prevent the distortion and disfigurement of the abrading wheel, which tends to occur after periods of long use, and thereby maintain cuts of consistent depth during the abrading process. A similar abrading disc 27, preferably of smaller diameter than the disc 23, is suitably fastened near the lower end of the spindle 8 and is provided on its under surface with a supporting plate 28 in a manner similar to the outlined above and for a similar purpose. It will be noted that the diameter of each supporting plate 26 and 28 is somewhat less than the diameter of its respective abrading wheel 23 and 27 so that the periphery of each wheel extends slightly beyond the edge of its supporting disc for the obvious purpose of providing unsheathed abraded surfaces 29 and 30 which, after being subjected to slight wear, will still retain their abrading properties without interference from the adjacent supporting discs. An additional element, shown as a metal disc 31, is fixed to the upper surface of the abrading disc 27 in a manner so as to rotate therewith, and is of greater diameter than either the abrading disc 27 or its supporting disc 28. This disc 31 forms, in effect, a circular lip around the upper edge of the periphery of the abrading disc 27, which acts as a gauge or limit plate to prevent the paper tube from elevating or climbing during rotation. Thus the length of the abraded surface, measured along the longitudinal axis of each tube, can be nicely controlled and maintained uniform throughout quantity production lots. While but a single gauge disc has been shown and described, it will be understood that two such discs may be used, the second disc assisting the first and being carried by the abrading disc 23. As shown, the abrading unit is constructed as one station of the well known dial machine, and accordingly the mechanism for feeding a paper or fibre tube between the two abrading surfaces comprises the usual rotating loading or feeding dial 32, rotatable about a vertical shaft or axis 33, and having a plurality of radially disposed fibre tube receptacles of pockets, indicated generally in the drawings by the bosses 34. Each boss 34 is formed integrally with and suitably spaced about the outer circumference of the loading dial 32. A hole 35 is drilled vertically through each boss 34 and through the corresponding portion of the loading dial 32 and a bushing 36 or receptacle lining fitted into the drilled hole 35. The inner cylindrical wall 37 of each bushing 36 thus constitutes a bearing surface for the rotation of a fibre tube 38 freely mounted therein. It will be evident that the receptacles or pockets 34 are, in effect, nothing more than open ended sleeves 36, which construction is for the purpose of effecting the automatic discharge of a finished tube. In order to prevent the discharge of the tubes before they have been abraded suitable supporting means is provided comprising a substantially flat surface 39 arranged immediately beneath the under surface of the loading dial 32 and of such size and configuration as to effect a supporting

slideway beneath the plurality of open ended sleeves 36 during that portion of their travel when tubes 38 are being fed thereto and conveyed to the abrading wheels 23 and 27. 40 indicates a relatively narrow circumferential ledge or tongue formed on the lower portion of the dial 32, said ledge comprising two bearing surfaces 41 and 42 substantially parallel to each other, adapted to engage similar bearing surfaces 43, 44 suitably grooved in the lower portion of the bed or frame 1. This tongue and groove construction in the adjacent relatively moving edges of the loading dial 32 and frame 1 constitutes means for maintaining the smooth and accurate operation of the co-operating parts.

Movement of the loading dial 32 is effected in any well known manner, such movement being preferably intermittent rotation for carrying the tubes 38 to the several loading stations including peripheral contact with the abrading wheels 23 and 27, and may be accomplished by the commonly used pawl and ratchet mechanism or equivalent mechanisms not shown.

Although the description of the loading dial 32 has been limited to the construction shown in the drawings, it is understood that the invention is not so limited and that its scope may cover the combination of an abrading unit with other commonly used loading means. Such a modification, too obvious to need illustration, would be the so-called straight line loading machine having an endless conveyor chain with receptacles therein for carrying the paper tubes into contact with the abrading wheels. Suitable automatic feeding means for feeding paper tubes to the receptacles on the loading dial or conveyor chain may be used in combination with the abrading unit. For the purpose of illustration only such means may comprise a suitably arranged hopper 45 having a delivery pipe 46 extending to a point immediately adjacent the loading dial receptacles, whereby a paper or fibre tube is automatically fed by gravity into each receptacle as it passes beneath the mouth of the pipe. It is understood, however, that other methods of feeding the tubes into the dial or chain receptacles may be used as, for instance, means for feeding the tubes up into the receptacles from the bottoms thereof.

The method of operation is believed to be obvious from the above description of the component elements, but for the sake of clarity a brief resume follows. Assuming that the motor 16 is running and that the spindle 9 is being driven by its pulley and belt connections; the spindle pulley 17 and belt 20 drive the spindle pulley 21, the speed ratio being one to one so that the speed of rotation of the spindle 8 is substantially the same as that of spindle 9. Rotation of the spindles 8 and 9 effects the rotation of the respective abrading discs 23 and 27. However the effective diameters of the wheels are different and consequently the peripheral or abrading surfaces of the respective wheels move relatively at different peripheral speeds. Thus, as the loading dial 32 or its receptacles 36 carry a freely rotatable fibre tube 38 into peripheral contact with the juxtaposed abrading wheels 23 and 27, the latter engage the periphery of the tube adjacent its upper edge in such a manner as not only to rotate the tube but also to support the tube independently of the support given by the sleeve receptacle 36. Moreover, due to the relative peripheral speeds of the abrading surfaces, the seized tube does not assume the speed of either

abrading surface but is compelled to rotate at a resultant peripheral speed; that is to say its peripheral speed is different from that of either abrading wheel. Accordingly an abrading action is effected between the respective surfaces whereby a substantially thin film or layer of fibre or paper is sanded or shredded off the surface of the tube. After the tube has been abraded it is carried by the loading dial 32 to other stations in the tube loading cycle and finally to a point beyond the end of the supporting slideway 39, whereupon the completed tube immediately drops out of its supporting sleeve 36 and is suitably discharged from the machine.

While the above description has been confined, for simplicity's sake, to a single abrading unit, adapted particularly to constitute one station of a dial or straight line loading machine, it will be understood that a plurality of such units having individual tube feeding means may be suitably assembled on a bed frame and driven from a single power source. Fig. 2 of the drawings shows a series of abrading units, in this case modifications of the unit of Fig. 1, suitably mounted on a single frame and connected together and driven from a common power source. Figs. 3, 4 and 5 show, in more detail, the construction and assembly of the modified units. It may be said at the outset that the assembly includes, in general, a plurality of similar abrading units denoted generally by numeral 52, suitably spaced along the assembly frame 50, and a dissimilar master abrading unit 53, so called because it controls in part the operation of the units 52. The master abrading unit 53 is shown mounted on the right-hand end of the assembly frame.

Referring to the drawings, a single power source for operating the assembled combinations is, in this case, a totally enclosed circular gear head motor 51 of substantially one-third rated horse power, having a shaft speed of approximately 357 revolutions per minute, suitably connected on the back of and at the left-hand end of the assembly frame 50 by a plurality of securing means 54, 54, etc. The particular motor or power source used and its location relative to the abrading units may be varied and a motor having different power characteristics may be installed to meet the requirements of size, location and other conditions peculiar to each installation. The motor shaft carries a wedge-belt single groove pulley 55 which is connected by a V-belt 56 to a wedge-belt single groove pulley 57 of the main drive shaft 58. Inasmuch as all the pulleys and belts shown in the drawings are substantially of the same configuration, the terms "pulley" and "belt" as hereinafter used shall be understood to mean a wedge-belt single groove pulley and a V-belt respectively unless otherwise denominated. The use of the wedge-belt type of pulley and V-belt is preferred for the purpose of including certain adjustable features in the invention as hereinafter disclosed, but it is to be distinctly understood that equivalent belts are contemplated.

The main shaft 58 is mounted in suitable bearings 59, 59, 59, at spaced points along the assembly frame and carries a plurality of spaced pulleys suitably keyed thereto. The series of pulleys 60 carry belts 61, which connect with corresponding pulleys of a series of delivery hoppers (not shown) adapted to deliver fiber tubes to the abrading units, as hereinafter disclosed. A second series of pulleys 62 are properly spaced along the main drive shaft 58, are keyed thereto, and

carry V-belts 63 which drive a corresponding series of capital pulleys 64 of the abrading units. In the drawings the diameters of the capital pulleys and the drive pulleys 62 are in the ratio of 5 to 2 to 3 respectively, whereby the speed of rotation of each capital pulley 64 is substantially one and one-half times that of its respective drive pulley 62.

The foregoing description has related to one 10 method of assembling and driving the plurality of abrading units from a single power source, but it is to be clearly understood that the present invention is not intended to be limited thereby and that suitable methods including other driving means and different speed ratios may be used 15 within the scope of this invention.

The extreme right-hand end of the main drive shaft 58, see Fig. 4, has keyed thereto a single groove pulley 65 for transmitting rotation to the 20 feeding dials as hereinafter described, said pulley being connected by a V-belt 66 to a pulley 67. The latter is of the greater diameter, the ratio being substantially 1 to 3, and is keyed in any well-known manner to a horizontally disposed stud shaft 68 rotatively mounted in a pair of bearings 69, 69 (see Fig. 3) bolted or otherwise secured in the lower part of the frame 50. Mechanism for transmitting intermittent rotation to the feeding dial includes a substantially solid 25 wheel or disc 70 rotatively secured to the opposite end of the shaft 68. A pin 72 (see Fig. 5) suitably riveted or otherwise secured at a distal radial point of the disc 70 and projecting from the face thereof constitutes an eccentric bearing 30 pin for reciprocating the connecting rod 76. To this end the pin 72 is mounted in the bearing 73 of a coupling-arm 74, the fore-end of the latter being suitably drilled and threaded to receive the screw threaded end 75 of the connecting 35 rod 76. The opposite end of the connecting rod (see Fig. 5) is suitably screw threaded into one end of a pivoted coupling-arm 77; the opposite end of the coupling 77 is bifurcated and the spaced parallel arms 78, 78 so formed (see Fig. 45) provided with axially aligned drilled holes adapted to receive a pivot pin 79 which pivotally connects the arms 78, 78 to the drilled tongue 80 of a block 81. Reciprocation of the connecting rod 72 thus effects reciprocation of the block 50 81 which is pivotally connected by a bolt 82 to one arm 83 of a bell crank lever. The latter is pivotally secured at its hub portion by a nut and washer, indicated generally by numeral 84 (see Fig. 4) to the extreme lower end of a vertical 55 spindle 85, the fit of the joined parts being such that the bell crank may oscillate freely about the spindle in response to the reciprocation of the pivoted block 81. The other arm of the bell crank lever carries a pivotally mounted pawl 86 60 adapted to be resiliently urged by a suitably arranged spring (not shown) to engage the teeth 87 of the ratchet wheel 88. The ratchet wheel 88 is suitably keyed or otherwise secured to the spindle 85 in the plane of the pawl, whereby oscillatory motion of the pawl effects step by 65 step or intermittent rotation of the ratchet wheel 88 which, in turn, transmits intermittent rotation to the spindle 85 and the loading dial carried thereby. Referring again to Fig. 4, the spindle 70 85 is shown rotatively mounted in the assembly frame by means of a flanged bearing block 89 suitably secured, as by countersunk bolts 90, to the assembly frame 50, and having a spindle bushing 91 pressed or sweated into each end of its axial bore. 92 represents a master sprocket

wheel for driving the sprockets of the feeding dials of the abrading combinations 52 as hereinafter described, and is keyed or otherwise secured to the spindle 85 between the lower end of the flanged bearing and the upper face of the ratchet wheel 88. The upper surface of the flange or collar 93 of the bearing block 89 is adapted to act substantially as a flat bearing surface for the lower end of the hub 94 of the fiber tube loading or feeding dial 95. The feeding dial is axially bored or drilled to receive the upper end of the spindle 85 and is made to rotate intermittently with the spindle 85 by providing a pin or key 96 joining the parts. The dial may be constructed as a substantially solid metal disc having a plurality of holes 97, 97, etc. drilled through its outer edge at spaced radial points around its periphery. A bushing or metal sleeve 98 of greater length than the thickness of the dial and having inwardly beveled or countersunk upper edges 99 is adapted to be pressed or shrunk into each drilled hole 97 of the dial, the upper edge of the bevel 99 being substantially flush with the upper surface of the dial and the lower portion of the bushing depending an appreciable length below the under surface of the dial to form, in effect, a sleeve for guiding and supporting a fiber tube carried therein. The inner diameter of each sleeve 98 is of such size that a fiber tube may be freely but smoothly slipped or dropped into or out of the sleeve for the purposes hereinafter disclosed. In the previous discussion relative to Fig. 1, these sleeves 98 have been termed, for the sake of clarity, receptacles or pockets and may be so termed hereinafter, but it is clearly understood that the terms "pocket" and "receptacle" designate merely an open ended cylindrical sleeve. The construction and purpose of the receptacles 98 is substantially similar to that of the receptacles already described, it also being necessary during a portion of the travel of a fiber tube to provide a surface on which the lower end or bottom of the tube may slide. In the present modification, this surface or slide-way is indicated in Fig. 5 by numeral 100 and comprises a flat semi-circular hardened plate mounted on the frame with its upper surface substantially flush with the surface of the frame.

The above description of the loading or feeding dial 95 has been given particularly in relation to the so-called master abrading unit 53, but the construction of the feeding dials of the units 52 is substantially the same and therefore a detailed description of each is believed unnecessary. Suffice it to call attention to the fact that the loading dial spindle 85 of the unit 53 is somewhat longer than the spindles of the loading dials of the units 52 for the obvious purpose of accommodating the pawl and ratchet mechanism previously described, and that the intermittent drive for each loading dial of the units 52 is effected by the sprocket and chain connections 101 and 102 between each unit driven from the master sprocket wheel 92. The master unit is further characterized by having a brake on the loading dial 95 comprising a band 103 and a brake shoe 104 adapted to encircle or partially encircle the hub portion 94 of the loading dial to prevent overrunning or backlash thereof. For this purpose an anchor, such as a vertical post or pin 105, is suitably fixed to the frame 50 and engaged by one end of the brake band 103, the opposite end of the band being moved or adjusted relative to the fixed end of the band by means of an ad-

justing screw 106 which tends to draw both ends of the band together.

The operation and function of the parts as described so far may be briefly summarized as follows: The rotation of the main shaft 53 effects the rotation of the pulley 65 which by its belt 66 drives the pulley 67 of the stud shaft 68. Rotation of this shaft causes the eccentric pin 72 to effect reciprocation of the connecting rod 76 which, in turn, swings the bell crank lever 83 to and fro about its spindle axis 85. The pawl 86 alternately engages and disengages the ratchet teeth 87 of the ratchet wheel 88 and hence transmits step by step rotation to the spindle 85. Step by step or intermittent rotation thus characterizes the motion of the feeding dial 95 and the master sprocket 92. It is believed evident that the above-described braking means of the loading dial 95 is desirable for the purpose of preventing any back lash or over-running of the dial which might arise due to the momentum of the moving parts.

Referring to Fig. 5, there is shown in detail the construction of the modified abrading means per se, and inasmuch as all the abrading means per se are identical, a description of one will suffice for all. 107 represents a substantially rectangular frame or table for supporting the abrading means per se and comprises a rectangular top 108 and legs 109, 109 whereby the table is bolted to a part of the assembly frame 50. The horizontally disposed top portion 108 has a pair of slots or openings 110 and 111 through which project the spindles of the abrading wheels which are adapted to be mounted below the top of the table 108. The slots 110 and 111 also permit the spindles and their abrading wheels to be adjusted relative to each other, as hereinafter disclosed. These slots or openings are substantially rectangular in shape and have rounded ends as indicated by the dotted lines 112 and 113 of Fig. 3. In addition to the slots a pair of narrow relatively shallow bearing-block guide grooves are milled or otherwise formed in the surface of the top 108 along its medial line, each groove being at opposite ends of the table as indicated by the numerals 114 and 115. A pair of spindle bearing-blocks 116 and 117 are adapted to be adjustably supported on the table, each block comprising a substantially vertical bearing post integrally mounted or secured to one end of a laterally projecting foot portion 118 and 119 respectively. A portion of the under-surface of each foot is provided along its medial line with an integrally formed longitudinal rib or tongue 120 and 121 respectively adapted to slide in the aforesaid guide grooves 114 and 115 of the table top whereby the foot of each block is restrained to move in a straight line. Each foot is itself provided with a relatively narrow slot, 122 and 123 respectively, of limited length and of suitable width to receive the adjusting bolts 124 and 125 respectively. The latter are threaded into holes in the table top and constitute means for securing each foot, or its respective spindle bearing block, in adjusted position relative to the other. Adjustment of the spindle bearing-blocks 116, 117 relative to each other along a common medial line is thus effected by loosening the bolt 124 and 125 of each integral foot portion 118 and 119 respectively and then sliding the one foot along the table top 108 toward or away from the other foot. The amount of relative movement is, in most instances, very small, being, for example,

the difference between the diameters of a 12-gauge and a 16-gauge shot shell. By using the well-known wedge-belt pulleys and V-belts for connecting the spindles to the driving means, such slight relative movement between the parts is readily taken up and a uniform drive maintained. An additional means for locking the foot plate 118 in an adjusted position comprises a bracket 126 suitably bolted at its lower end to the leg 109 and having a threaded hole 127 at its upper end substantially in line with the rear end of the foot plate 118. A bolt 128 is threaded into the hole 127 and may be made to butt against the rear end of the foot plate 118 so as to restrain the latter from any inadvertent dislocation. As indicated in the drawings, each bearing-block or post 116, 117 has a pair of bushings 129, 129 and 130, 130 respectively, pressed or otherwise seated in the opposite ends thereof for rotatively supporting the vertical spindles 131 and 132 of the juxtaposed wheel 133 and 134 respectively. The wheel 133 is an abrading wheel and may comprise a wooden disc having a band of abrasive material 135 glued or otherwise secured around its periphery. Since the abrasive material is subject to severe wear and relatively rapid deterioration, it is necessary to provide for the facile interchange of a plurality of similar wheels, each of which carries the abrading material. To effect this end, each disc 133 is provided with an axially drilled hole 136 whereby the disc may be slipped over a square hub portion 137 on the lower end of the spindle 131. A pair of metal hubs or washers 138, 138, each having a square axial hole of substantially the same geometrical configuration and measurements as the square hub of the spindle 131, are adapted to be placed each on one side of the disc 133; the assembled parts are mounted on the square hub 137 of the spindle 131 and secured thereon by the nut 139, the washers 138, 138 acting substantially as keys to rotatively connect the disc to the spindle. The friction wheel 134 is preferably smaller than the abrading wheel 133, the ratio of diameters being substantially 1 to 2 respectively, and comprises an axially drilled disc having a hub portion 140. The disc is adapted to be slipped onto the lower end of the spindle 132 and keyed thereto by means of a radially disposed screw (not shown) threaded into the hub 140. The periphery or rim of the disc 134 is shown provided with a relatively resilient friction surface 141, as, for example, a rubber band or tire; however, for the purposes of this invention, the disc 134 may be formed of a substantially solid rubber composition material.

It will be understood that whereas the above description has been of the particular abrasive wheels shown in the drawings, the invention is not so limited but may conceivably include abrasive wheels of other well-known materials and constructions.

As shown in Fig. 5, the upper end of the vertical spindle 131 is provided with two single groove pulleys 142 and 64 keyed at their hub portions 143 and 144 respectively to the spindle 131 for driving the abrading wheel 133, the upper or so-called capital pulley 64 being superposed on the lower pulley 142 and driven by belt 63 from the pulley 62 on the main drive shaft 58, as previously described. In the drawings the ratio of diameters of the pulleys 142 and 64 is substantially 4 to 2½. 145 represents a single groove pulley for driving the friction disc 134 keyed at its hub portion 146 to the upper end of

the spindle 132 and connected by a V-belt 147 to the drive pulley 142, the ratio of diameters of the pulleys 142 and 145 being substantially 1 to 2. While the particular types of pulleys and belts shown in the drawings and the ratio of pulley diameters are as described, it is to be clearly understood that the invention is not limited to the particular driving means and speed ratios shown, but comprehends equivalent elements and combinations.

10 The pipe 148 (see Fig. 4) represents the commonly used feed pipe for delivering fiber or paper tubes to the loading dial and extends from a point near the upper surface of the loading dial 95 at which a tube receptacle or pocket 98 is moved into tube receiving position. A suitable angle bracket 149 having a vertically disposed leg 150 is bolted or otherwise secured to the assembly frame 50, the leg 150 being formed substantially arcuate in cross section to effect a semi-cylindrical surface adapted to partially embrace the outer surface or wall of the feed pipe at its mouth 151 to prevent the latter from vibrating or otherwise moving out of axial alignment with the tube receiving pockets 98. The mouth 151 of the feed pipe 148 is shown as a separate short length of pipe or thimble secured to the end of the feed pipe 148 by a threaded coupling 152.

15 A detailed explanation of the method of operation of the abrading unit per se is believed unnecessary in the light of the foregoing description, it being thought self-evident that as the fiber tubes are fed by gravity from a hopper through the feed pipe 148 into the axially aligned tube receptacles 98 of the loading dial 95, the fiber or paper tubes drop through the sleeves 98 until brought to rest on the slideway 100 and are then made to slide intermittently along said slideway by the pawl and ratchet drive of the loading dial 95 to a position between the spaced peripheral surfaces of the two wheels 133 and 134. The paper tube, being freely retained in its receptacle or sleeve 98, is instantly seized and rotatively supported by the juxtaposed surfaces of the wheels. Inasmuch as the latter are rotating relatively at different peripheral speeds, they transmit a resultant peripheral speed to the supported tube. As previously described, in connection with the operation of the abrading unit of Fig. 1, the effect of rotating the fiber or paper tube between two surfaces moving relatively at different peripheral speeds, one of said surfaces having abrasive properties, is to cause a rubbing or abrasive action to take place between the surfaces of the tube and the wheels whereby a portion of the fiber or paper is removed from the tube. After the tube has been thus abraded it is then carried along to a point in its travel beyond the end of the supporting slideway 100, whereupon the abraded tube immediately drops by gravity out of its sleeve receptacle 98 and is suitably discharged from the machine.

20 25 30 35 40 45 50 55 60 65 70 A further modification designed primarily to facilitate the adjustment of the abrading wheels relative to each other is schematically represented in Fig. 6 and Fig. 7. 160, 160 represent a pair of substantially parallel spaced arms each pivotally mounted in the same horizontal plane and on a vertical axis or shaft 161 at a point intermediate its ends. A suitable abrading wheel 162 is adapted to be rotatably mounted on a vertical drive shaft 163 at one end of each arm—the two abrading wheels being normally urged into tangential contact with a shot shell tube by a suit-

able spring 164 connected between the arms and forward of the vertical shafts 161, 161. The usual belt and pulley drive means for the abrading units is indicated, in general, by the numerals 165 and 166 respectively. It is also understood that the loading or feeding dial (not shown) described in connection with the foregoing abrading units is also adapted to be used in combination with this modification. An adjusting screw 167 is mounted on the frame adjacent the rear end of the arm 160 and has a tapered end or point adapted to be brought to bear against the side of the adjacent arm for the purpose of turning the latter about its axis and thereby adjusting the spacing of the abrading wheels for abrading different gauge shot shells. The element 168 represents an additional adjusting means and comprises a pivoted cam surface actuated by a suitable thumb screw or lever 169 and adapted to co-operate with a cam surface suitably formed on the adjacent end of the second arm 160. The purpose of the pivoted cam surface is to overcome any initial destructive abrading effect caused by improper spacing of the wheels which may occur whenever a new and relatively thicker abrading band is put on the wheels. By rotating the lever 169 a camming action is effected between the adjacent cam surfaces of the pivoted cam and the lever whereby the abrading surfaces are spread apart by an amount substantially equal to the increased thickness of a new abrasive band and hence any destructive abrading of the initial shells may be avoided. Thereafter and as soon as the new abrading band has been slightly worn the cam surface may be pivoted back to its original position to thereby maintain the proper spacing of the abrading surfaces.

From the foregoing descriptions made with reference to the drawings, it is believed to be evident that the present invention discloses a new and novel method and means for automatically abrading limited areas on the outer periphery or surface of a fiber or paper tube; that the method embodies a new combination abrading unit for conveying a freely mounted paper tube into peripheral contact with a pair of surfaces, at least one of which has abrasive properties; and moving the surfaces relatively at different speeds so that the tube is supported simultaneously at opposite tangential points of its surface and caused to rotate at a resultant peripheral speed which is different from that of either abrading wheel, whereby an abrading action is effected between the surfaces of the wheels and the tube, and portions of the tube are sanded or shredded off.

What is claimed is:

1. In a shot shell tube abrading machine, a wire brush abrading wheel, a second wire brush abrading wheel rotatably mounted in spaced relation to said first abrading wheel; means for driving the first abrading wheel, means driven by said first abrading wheel and connected to the second wheel to drive the latter at a different peripheral speed, metal discs secured on the under side of said abrading wheels to support the wire brushes, a rotatable feeding dial to move shot shell tubes intermittently into rotatively supported contact with said abrading wheels, a metal disc secured on the upper side of at least one abrading wheel to limit the elevation of the shot shell during its rotation, and means to rotate said feeding dial intermittently.
2. In a shot shell tube abrading machine, a fixed table; a transfer dial rotatably mounted in a horizontal plane above said table, said dial having peripherally spaced apertures provided with bushings for supporting shot shell tubes, the bases of which rest on said table; abrading means comprising rotatable members having spaced surfaces, at least one of said surfaces having abrasive properties; means to rotate said members at different peripheral speeds; and means to index the rotation of said transfer dial whereby said tubes are moved successively over said table into engagement with the rotating spaced surfaces, said surfaces being constructed and arranged simultaneously to peripherally engage a limited area of a tube rotatably supported in the bushing of said transfer dial and by said engagement to abrade said tube.
3. In a shot shell tube abrading machine, a fixed table; a transfer dial rotatably mounted in a horizontal plane above said table, said dial having peripherally spaced apertures provided with bushings for supporting shot shell tubes, the bases of which rest on said table; abrading means comprising rotatable members having spaced surfaces, at least one of said surfaces having abrasive properties; a power driven belt to rotate one of said members; a second belt connecting said members to drive one of said members by the other member and at a different peripheral speed; and means to index the rotation of said transfer dial whereby said tubes are moved successively over said table into engagement with the rotating spaced surfaces of said members, said surfaces being constructed and arranged simultaneously to peripherally engage a limited area of a tube rotatably supported in said bushing and by said engagement to abrade said tube.

HARVEY J. HACKMAN.

CERTIFICATE OF CORRECTION.

Patent No. 2,350,553.

June 6, 1944.

HARVEY J. HACKMAN.

It is hereby certified that error appears in the printed specification of the above numbered patent requiring correction as follows: Page 2, first column, line 19, before the word "outlined" strike out "the"; line 55, for "of pockets" read --or pockets--; page 5, first column, line 21, for "juxtaposed wheel" read --juxtaposed wheels--; page 6, second column, line 30, claim 2, after "surfaces" first occurrence and before the comma, insert --of said members--; and that the said Letters Patent should be read with this correction therein that the same may conform to the record of the case in the Patent Office.

Signed and sealed this 21st day of November, A. D. 1944.

Leslie Frazer
